HYDRAULIC BRAKE

Warren R. Tucker, Dayton, Ohio, assignor to The Hydraulic Development Corp. Inc., Wilmington, Del., a corporation of Delaware

Application May 23, 1940, Serial No. 336,792

4 Claims. (Cl. 100—71)

This invention relates to presses, and in particular to presses having a plurality of spaced pressing plungers connected with one and the same platen. Such machines, which are particularly useful for forming long extended parts, such as airplane wings, and which include the so-called press brakes, shear brakes and bending brakes, have heretofore been operated mechanically to insure a uniform movement of the ends of the platen or beam as far as possible.

Nevertheless, with the said known presses, an asynchronous movement of the spaced pressing plungers has often been encountered with the result that one end of the platen or beam is moving ahead of the opposite end, thereby causing a cocking of the platen or beam and great wear of the plungers in addition to spoiling the workpiece.

Moreover, the said mechanical presses are relatively complicated in construction and expensive in manufacture.

Accordingly, it is an object of the present invention to provide a machine which will overcome the above identified drawbacks.

It is a further object of the invention to provide a multi-plunger press of the above identified character, in which synchronous movement of the spaced plungers connected with the ends of the pressing platen, bending beam or shear is assured by hydraulic means.

Another object of the invention is to provide a machine, as set forth in the preceding paragraph, in which the fluid expelled by the pressing plungers during the working stroke thereof, is controlled so that the quantity of fluid escaping from each working cylinder is the same.

A still further object is to provide a press for forming a long extended workpiece, which comprises a plurality of spaced cylinder piston assemblies having throttling means associated therewith for throttling the exhaust of said cylinder piston assemblies, so as to insure synchronous movement of the parts of said cylinder piston assemblies.

A still further object of the invention consists in the provision of a press of the above identified type in which the pressing members are automatically slowed down at the end of the pressing operation, and are brought to a standstill shortly thereafter.

It is also an object of the invention to provide a press having a plurality of spaced plungers in which the plungers are associated with hydraulic means for maintaining synchronous

movement thereof, and with further hydraulic means for slowing down the movement of said plungers at the end of their retraction stroke.

These and other objects and advantages of the invention will appear more clearly from the following specification in connection with the accompanying drawings, in which:

Figure 1 illustrates the assembly of a press according to the present invention.

Figure 2 shows, on a somewhat larger scale, the left portion of the machine illustrated in Figure 1.

Figures 3 and 4 are further embodiments of a cushioning device used in connection with the present invention.

Figure 5 diagrammatically illustrates a hydraulic circuit for a press according to the invention.

General arrangement

20 In general, the press, according to the invention, comprises a plurality of spaced hydraulically operable plungers connected with a press platen, beam or shear, said plungers being associated with throttling means adapted automatically to provide for an equal discharge to exhaust by all pressing plungers. More specifically, when one pressing plunger connected with one end of the pressing platen, bending beam or shear, tends to run ahead of another pressing plunger connected with the opposite end of the pressing platen, bending beam or shear, the said throttling means control the fluid expelled by the respective pressing plunger so as to brake the latter, thereby maintaining synchronous movement of all plungers.

Structural arrangement

Referring to the drawings in detail, 1 designates the press bed connected with the press head 2 by means of strain rods 3 and nuts 4. Connected with the press head by screws 5, or by any other convenient means, is a cylinder head 6. Similarly, a cylinder head 7 is connected by screws 8 with the press bed 1. Reciprocably mounted in the cylinder heads 6 and 7 are pistons 9 and 10 respectively interconnected by means of a ram 11. The cylinder piston 9 corresponds in its construction to the piston 10, so that a description of the latter will be sufficient.

40 Fixedly carried on the outward end of each piston 9 and 10 is a plate 12 surrounding a cushioning valve rod 13, which extends through the pistons and the ram 11 and beyond the pistons. The ends of the rod 13 extend slidably through extremely close fitting guides 14 and 15 formed

in the ends of the cylinders 6 and 7 respectively, and also extend into the cavities 18 and 17 formed in the heads of the cylinders 6 and 7 respectively.

As will be seen from the drawings, the plates 12 surround the rod 13 with considerable clearance, which is comparable to the clearance existing between the ram 11 and the rod 13. The plates 12 are each formed with a radially extending groove 18, which serves to admit the pressure fluid into the pressure cavities 19 and 20 formed in the cylinders 6 and 7 respectively, in a manner which will presently appear.

The plates 12 are formed with an annular abutting portion 21, which is adapted to abut the inner faces 22 and 23 of the ends of the cylinders 6 and 7 respectively. The plates 12 are each further provided with an annular recess within which is received a floating ring 24. The floating ring 24 is held in place by the plate 12, and is allowed to move radially to prevent bending of the valve rod 13 due to any misalignment thereof with the ring 24 and the guides 14 and 15. The rings 24 slidably engage the surfaces of the rod 13 with an extremely close clearance, whereby the escape of pressure fluid from the ring along the valve rod 13 is prevented. This construction is extremely reliable and compact and allows the valve rod to shift readily without having the seal destroyed. It will be understood that the rings 24 likewise engage the surfaces of the plates 12, and of the pistons 9 and 10 slidably, but with extremely close clearance.

The valve rod 13 has axial holes 25 and 26 respectively, drilled from its ends, and the ends of the valve rod 13 are machined with slots 27 and 28 respectively connecting with the holes 25 and 26. On the upper end of the rod 13, toward the inward end of the hole 25, are four radial connecting holes, these connecting holes 29 being relatively large in diameter and adapted to freely connect the hole 25 with the chamber 19 in the cylinder 6. The lower end of the rod 13 is similarly provided with identical holes 30.

Located outwardly from these holes 29 and 30 are a series of longitudinally spaced connecting holes 31 and 32 respectively, being progressively more closely spaced, and progressively smaller in diameter as one proceeds outwardly from the holes 29 and 30. These holes 31 and 32 are preferably disposed in a single row on only one side of the rod 13 instead of extending into four directions as do the holes 29 and 30; and these holes 31 and 32 likewise communicate with the holes 25 and 26.

The ends of the rod 13 are adapted to abut against threaded plugs 33 and 34, which are threadedly mounted in the ends of the cylinders 6 and 7 respectively. These plugs 33 and 34 are covered by removable end caps 35 and 36 respectively, which serve to prevent unauthorized changes in the position of the threaded plugs, and also serve to prevent oil leakage around the threads of the plugs.

Communicating with the chambers 16 and 17 are passageways 37 and 38 respectively, which are adapted to act as either inlet or discharge conduits depending upon in which direction the ram or plunger 11 is being moved.

The plugs 33 and 34 are so adjusted that when the rod 13 abuts against one of them, the slot 27 or 28 in the other end of the rod 13 is adapted to freely interconnect the passageways 37 or 38, and the chamber 16 or 17 with the pressure cavities 19 or 20, this being accomplished by hav-

ing slots 27 and 28 of such a length that the slots extend into the interior of the chamber 19 or 20. This is indicated at the upper end of Figure 2, wherein the slot 27 has a considerable portion disposed within the chamber 19, and hence is adapted to allow free entry of the pressure fluid from the passageway 37 into the chamber 19, where it may act upon the piston 9 to move the same away from the fluid inlet.

When the rod 13 abuts either of the plugs 33 or 34, its slot 27 or 28 is in non-communication relationship with the pressure cavities 19 or 20, as is indicated in the lower portion of Figure 2, whereby, when the pressure fluid is first admitted, its first action is to move the rod 13 axially into engagement with the other plug 33 or 34. This action also serves to press the slot 27 or 28 in communication with the chamber 19 or 20, thereby allowing the pressure fluid to act upon the piston 9 or 10.

As will be seen from Figure 2, the ram or plunger 11 is provided with collars 39 and 40 engaging correspondingly shaped recesses in a member 41 threaded into the platen or beam 42. The beam or platen 42 is provided with bushings 43 slidably engaging the strain rods 3 for guiding the platen or beam 42. In this way, movement of the pistons 9 and 10 will cause a corresponding movement of the platen or beam 42. Packing material 44 and 45, compressed by glands 46 and 47, prevents leakage from the cylinders 6 and 7.

While according to the embodiments of Figure 2, the ram or plunger 11 is brought to a standstill by engagement of its plates 12 with the adjacent surfaces 22 and 23 respectively, in other words in a mechanical manner, according to Figures 3 and 4, hydraulic stop means are provided.

The parts of Figures 3 and 4, which are similar to those described in connection with Figure 2, are designated with the same reference numerals, however, with the additional character *a* and *b*, respectively.

The cylinder 1a of Figure 3 comprises a cylinder chamber 48 in which the piston 10a is reciprocably mounted. A conduit 49 communicates with the upper portion of the cylinder chamber 48, whereas the lower portion of the cylinder chamber 48 communicates through a conduit 50 with a tonnage control valve 51. The tonnage control valve 51 comprises pressure responsive means, which at the attainment of a predetermined pressure in the chamber 48, below the piston 10a, causes a change in an electric circuit comprising means for reversing the direction of delivery of the pressure pump, thereby initiating the retraction stroke of the ram or plunger 11a.

The tonnage control valve 51 does not form a part of the invention, and for a more detailed description thereof, reference may be had to patent application, Serial No. 214,772 to Walter Ernst, filed June 20, 1938.

A cylinder 1a, comprising a boss 52 with cavities 53 which communicate with a conduit 38a extending into the cavities 53, has a valve rod 13a, which is adapted to engage an adjusting screw 34a. The longitudinal bore in the lower end of the valve rod 13a communicates with a lateral bore 53a adapted to allow passage of fluid from pipe 38a into cylinder 1a when the valve rod 13a is in its upper position. Leakage along the adjusting screw 34a is prevented by packing material 54 compressed by a gland 55 and a tightening nut 56.

The holes 32a in the rod 13a are so arranged

that they are completely covered up before the piston 10a can engage the lower surface of the cylinder chamber 48. In this way, there will always be a fluid cushion between the lower portion of the cylinder chamber 48 and the adjacent surface of the piston 10a.

The embodiment of Figure 4 is very similar to that of Figure 3, but differs in that the tonnage control valve 51, together with the conduit 50, is replaced by the mechanism shown on the right hand of cylinder 1b, illustrated in Figure 4. According to this mechanism, the adjusting screw 34a is replaced by a plunger 57 connected by means of a bracket 58 with a limit switch 59. The limit switch 59 has a lever 60, supporting a roller 61 adapted to be engaged by any convenient means, for instance, the actuating member 62 adapted to be operated by the beam or platen 42 in cooperation with the movement of the pressing plungers 11. The plunger 57 may be adjusted relative to the cylinder 1b, and the limit switch 59 may be adjusted relative to the actuating member 62, by lifting or lowering the bracket 58.

To this end, the bracket 58 has connected therewith a nut 63 engaged by an adjusting screw 64 having a handle 65 and being rotatable, but not axially slidably in a fixed bearing 66. Rotation of the screw 64 in one or the other direction will lift or lower the bracket 58, thereby determining the point where the end of the valve rod 13b will engage the adjacent front face of the plunger 57.

Referring now to Figure 5, it will be noticed that the passageway 37 of the cylinder 6 is connected by means of a conduit 67 with the passageway 37 of the cylinder 6c. Similarly, the passageway 38 of the cylinder 7 is connected by means of a conduit 68 with the passageway 38c of the cylinder 7c. The lower portion of the cylinder chamber 19, below the piston 9, is connected by means of a conduit 69 with the lower portion of the cylinder chamber 19c, below the piston 9c.

The upper portion of the cylinder chamber 20, above the piston 10, communicates through a conduit 70 with the upper portion of the cylinder chamber 20c, above the piston 10c.

Branching off the conduit 67 is a conduit 71 leading to a shuttle valve 72 with a cylinder chamber 73 and a shiftable member 74, a branch conduit 75 connecting the lower portion of the valve chambers 73 with the conduit 68. The upper and lower portion of the valve chamber 73 may communicate with a fluid tank 76 through conduits 77 and 78. A conduit 79 leads from the fluid tank 76 to the suction side of a pump 80, the pressure side of which communicates through a conduit 81 with the middle portion of the valve cylinder chamber 73.

As will be seen from Figure 5, the position of the valve member 74 will determine whether pressure fluid from the pump 80 is passed into the conduit 71 or the conduit 75. A third line 82 leads from the fluid tank 76 through a pressure relief valve 83 to the conduit 81. The conduit 81 also communicates with the conduit 70 through a conduit 84.

The throttling device used according to the present invention in connection with presses of the type involved, comprises a manually adjustable choke valve 85 having a cylinder 86 with a port 87 communicating through a conduit 88 with the conduit 75. Extending into and adjacent the port 87 is an adjustable screw 89. The adjustment of screw 89 relative to the port 87 leaves a smaller or larger opening through which fluid may pass from the interior of the choke valve 85.

into the conduit 88. The interior of the choke valve 85 communicates through a conduit 90 with an automatic feed control valve, generally designated 91. This feed control valve, which in itself, does not form a part of the invention, and which is more fully explained in Patent 2,146,537 to Farnham, comprises a cylinder 92 with spaced cylinder chambers 93, 94, 95 and 96. Mounted in the cylinder chamber 96 of the valve 91 is a spring 97, engaging with its lower end the bottom of the chamber 96, while the upper end of the spring 97 engages the lower portion of a plunger 98 passing through the chambers 95 and 94, and normally extending into the chamber 93.

The plunger has a longitudinal transverse bore 99 with a tapered upper portion 100. The longitudinal bore 99 is adapted to effect communication between the chambers 94 and 95. The chambers 93 and 94 communicate with the conduit 90 by means of passageways 101 and 102 respectively. The chamber 95 communicates with a conduit 103 leading into the conduit 68, which latter comprises two in opposite direction opening check valves 104, 105. The check valves 104 and 105 are so arranged that the conduit 75 communicates with the conduit 68 between the said check valves. The valve 91 furthermore comprises, at the lower portion of the chamber 96, a breather opening 106.

Symmetrically to the choke valve 85 and the feed control valve 91, are provided a choke control valve 106 and a feed control valve 107. The construction of the choke control valve 106 and feed control valve 107, fully corresponds to that of the choke valve 85 and the feed control valve 91, so that a further description of the valves 106 and 107 is superfluous. Similarly to the choke valve 85, the choke valve 106 communicates through a conduit 88a with the conduit 75 and through a conduit 90a with the passage 101a and 102a of the feed control valve 107, which latter communicates through a conduit 103a with the conduit 68.

Operation

Assuming that the different parts of the device occupy the position shown in Figure 5, which position corresponds to the end of a downward stroke, and that it is now desired to perform a retraction stroke, the valve member 74 is shifted so that the conduit 75 communicates with the conduit 81, while communication between the conduit 71 and 77 is established. Pressure fluid will then be delivered by the pump 80 through the conduit 81 and the conduit 75, and will flow through the check valve 104 and the conduit 68, into the passageway 38 where it will act upon the slot 28 of the valve rod 13.

The pressure acting upon the slot 28 will lift the valve rod 13 to such an extent that it abuts the nut 33. After this movement has been effected, the slot 28 will communicate with the lower part of the chamber 20, so that the fluid pressure delivered by the pump 80 through the conduit 68 will act upon the lower area of the piston 10. Since the lower area of the piston 10 is larger than the upper area of the piston 10, the latter will be moved upwardly, although the upper area of the piston 10 communicates through the conduit 70 and the conduits 84 and 81 with the pressure side of the pump 80.

The fluid expelled by the piston 10 will flow through the conduits 70 and 84 into the conduit 75 and be added to the fluid delivered by the pump 80, thereby aiding the retraction stroke.

of the piston 10. This results in a speeded up retraction stroke of the ram 11.

It is, of course, understood that a part of the fluid delivered by the pump 80 will pass through the check valve 105, and the conduit 68a into the passageway 38a, where it will actuate the piston 10c in the same manner as described in connection with the piston 10.

During the upward movement of the ram 11, the piston 9 connected with the ram 11, will likewise be moved upwardly. During this operation, the space below the piston 9 will be filled by fluid from the fluid tank 76, due to the suction effect caused in the conduit 108 and 69. The fluid expelled by the piston 9 enters the passageways 29 and ports 31 and passes through the bore 25 and the slot 27 into the passageway 37. From here it flows through the conduit 67 and 71 through the valve 72 and the conduits 77 and 78 into the fluid tank 76.

Similarly, fluid passes through the conduits 108 and 69 into the space below the piston 9c while fluid expelled by the piston 9c passes through the holes 29c, bores 31c and slot 27c into the passageway 37c. From here it escapes through the conduit 67, 71, valve 72 and conduit 77 and 78 into the fluid tank 76. Since during this retraction stroke of the rams 11, 11c no load acts upon the said rams, the latter will move substantially synchronically.

When the pistons 9 and 9c approach the last portion of their upward stroke, they gradually cover up the ports 31, thereby restricting the escape of fluid from the upper portion of the cylinder chambers 19, 19c, and gradually slowing down the movement of the rams 11, 11c. When the last port 31 is covered up, no fluid can escape any more from the cylinder chambers 19, 19c, and the rams 11, 11c come to a halt. In this position, the pistons 9, 9c engage the upper abutment surfaces 22, 22c of the cylinders 6, 6c. Excess fluid now delivered by the pump 80 will be discharged through the fluid pressure relief valve 83 into the fluid tank 76.

If it is now desired to perform a working stroke, the valve member 74 is shifted into the position shown in Figure 5. As will be clear from the said figure, pressure fluid is now delivered by the pump 80 through the conduits 81, 71 and 67 into the passage 37, and 37c where it acts upon the slots 27 and 27c of the valve rods 13, 13c. The valve rods 13, 13c are moved downwardly by the pressure acting upon the said slots 27, 27c until the valve rods 13, 13c engage the plugs 34, 34c. As soon as this position is reached, the pressure fluid in the passageways 37 and 37c passes through the slots 27, 27c into the upper portion of the chambers 19, 19c where it acts upon the pistons 9 and 9c to move the same downwardly. The fluid pressure below the pistons 9, 9c escapes through the conduits 69, 108 into the fluid tank 76.

The pistons 10 and 10c connected with the pistons 9, 9c by means of the rams 11, 11c likewise move downwardly, and the space above the pistons 10 and 10c is filled by pressure fluid delivered by the pump 80 and flowing through the conduits 81, 84 and 70. In other words, the pressure fluid entering the upper portion of the chambers 20 and 20c directly aids the pressure fluid acting upon the upper surface of the pistons 9, 9c. The fluid expelled by the pistons 10, 10c during the downward movement of the said pistons passes through the holes 30, 30c and the ports 32, 32c into the bores 26, 26c. From here it

escapes through the slots 28, 28c into the passageways 38, 38c. From there the fluid passes through the conduits 68, 108 and 68a, 108a into the chambers 95 and 95a of the feed control valves 5 91, 107 respectively. The valves 104 and 105 bar communication between the conduits 68, and 68a, and the conduit 75. The fluid in the chamber 95 of the valve 91 now passes through the slot 93 into the chamber 94 and from there through the conduit 90 into the choke valve 85. From here the fluid passes through the choke valve port 87 into the conduits 88 and 75 through the valve 72 and the conduit 78 into the fluid tank 76.

According to the adjustment of the screw 89, 15 a greater or smaller quantity of fluid will be allowed to pass through the port 87. Similarly, the fluid in the chamber 95a passes through the slot 93a, the chamber 94a, the conduits 88a, the choke valve 106 and the conduits 88a, 75, the 20 valve 72 and conduit 78 into the fluid tank 76.

Supposing now, that the workpiece is so located, with respect to the platen or beam connected with the rams 11, 11c that the workpiece 25 re-acts only against the ram 11c, or with a substantially greater force against the ram 11c than against the ram 11. In this instance, the ram 11 tends to run ahead of the ram 11c which, if it were possible, would result in a cocking of the platen. However, according to the present invention, this is prevented in the following manner. As soon as the ram 11 and thereby the piston 10 tends to run ahead of the ram 11c, the pressure in the conduit 68 and 108 tends to increase. This pressure is conveyed through the passage 102 upon the plunger 98 and moves the latter against the thrust of the spring 97 downwardly, to a certain extent. This causes a reduction of the orifice, effecting communication between the slot 93 and the chamber 94, and 35 thereby restricts the quantity of fluid which may 40 pass from the conduit 108 into the conduit 93, so that only the same quantity of fluid as before may pass through the valve opening 87. In other words, the fluid escaping from the choke 45 valves 85 and 106 is equalized, so that synchronous movement of the rams 11 and 11c is assured.

As soon as the pistons 10 and 10c approach the end of their downward stroke, they will gradually cover up the holes 30, 30c and bores 32, 32c, thereby gradually slowing down the movement of the rams 11, 11c, and finally bringing the said rams to a halt when all holes and ports 30, 30c, 55 32, 32c are covered up. In this position, the pistons 10 and 10c engage the lower abutting surfaces 23 and 23c of the lower portions of the cylinders 7, 7c. Any excess fluid delivered by the pump 80 is then conveyed through the pressure relief valve 83 into the tank 76.

While, according to the structure of Figure 5, throttling means are provided only in the exhaust conduits 68, 68a, it is, of course, possible to provide similar throttling devices in the conduit 67. However, since as previously mentioned 65 no substantial load acts upon the rams 11, 11c during the upward movement, there is no danger of a cocking of the platen so that generally, no throttling devices are required in the conduits 67.

Although the operation with regard to Figure 70 5 has been described so that the pistons 9, 9c and 10, 10c engage at the end of their strokes, either the abutments 22, 22c of the cylinders 6, 6c, or the abutments 23, 23c of the cylinders 7, 7c, it is self-understood that by adjusting the plugs 33, 33c and 34, 34c, the movements of the

pistons 9, 9c or 10, 10c may be brought to a halt before they engage the respective abutments.

If it is desired to reverse the movement of the platen before all ports 31, 31c or 32, 32c have been closed up by their respective pistons, the embodiment of Figure 3 may be employed. According to this embodiment, the attainment of a predetermined pressure in the lower space of the chamber 48, below the piston 10a, will 5 actuate the tonnage control valve 51, thereby automatically shifting the valve 74 and causing the reverse movement of the platen.

It is also understood that the shifting movement of the valve member 74 may be effected automatically in any other desired manner, for instance, by actuation of the platen, when the latter has reached a predetermined point.

With respect to the last mentioned embodiment where the platen, or a member connected with the platen actuates means such as a limit switch for reversing the movement of the platen, it may be desired to enable a simultaneous adjustment of the valve rod, i. e. the degree of the slow-down movement of the respective pistons and the time when the limit switch is actuated. Such an adjustment is made possible by the device shown in Figure 4. To this end, the hand-wheel 65 and the screw 64 connected therewith has merely to be rotated, whereby the bracket 58 carrying the abutments 57, and the valve rod 13b, and the limit switch 59 to be operated by the member 62, will be lifted or lowered in accordance with the direction in which the hand-wheel 65 is rotated. A lifting of the abutment 57 will cause an earlier stop of the piston 10b, while the lifting of the limit switch 59 will enable an earlier actuation thereof by the member 62 connected with the platen. A lowering of the bracket 58 will, of course, have the opposite effect.

It will be understood that I desire to comprehend within my invention such modifications as may come within the scope of the claims of the invention.

Having thus fully described my invention what I claim as new and desire to secure by Letters Patent, is:

1. In combination in a press, hydraulic motor means, a platen or beam connected with said motor means and reciprocable thereby, control-

ling means comprising metering ports and passageways associated with said motor means and adapted to cooperate with said motor means to stop the latter, switch means operable by said platen or beam at a predetermined point, and adjusting means adapted simultaneously to adjust the controlling means and said switch means for determining the end of the working stroke of said platen or beam and the initiation of its retraction stroke.

2. In combination in a press, spaced hydraulic motors, a platen or beam interconnecting said motors and adapted to be reciprocated thereby, a fluid source for supplying pressure fluid to said motors to actuate the same, hydraulic means adapted to maintain synchronous movement of said motors, a plurality of valve rods having metering ports and passageways therein, hydraulic means associated with said valve rods for hydraulically stopping said motors, switch means operable by said platen or beam for reversing the direction of said motors, and means adapted simultaneously to adjust said valve rods and switch means for varying the point at which the platen or beam is stopped and its movement reversed.

3. In combination in a press, hydraulic motor means, a press platen reciprocable by said motor means, means operable in response to a predetermined travel of said motor means for slowing down said platen near the end of its working stroke, control means for varying said slow down operation, reversing means for initiating the reversal of said platen, and adjusting means common to both said control means and said reversing means for adjusting the same.

4. In combination in a press, hydraulic motor means, a platen or beam reciprocable by said motor means, reciprocable means operable to reduce the speed of said platen in response to the travel of the latter over a predetermined distance, control means associated with said reciprocable means for varying said predetermined distance, reversing means for reversing the travel of said platen, and an adjusting member operable to effect both an adjustment of said control means and of said reversing means.

WARREN R. TUCKER.
